(74) *Attorney, Agent, or Firm* — Egbert Law Offices, PLLC(57) **CLAIM**

The ornamental design for a pushcart, as shown and described.

DESCRIPTION

FIG. 1 is a perspective view of a pushcart showing my new design.

FIG. 2 is a front view thereof;

FIG. 3 is a rear view thereof;

FIG. 4 is a side view thereof;

FIG. 5 is an opposite side view thereof; and,

FIG. 6 is a top view thereof.

The features presented in broken lines represent unclaimed portions of the pushcart and form no part of the claimed design. The bottom surface of the pushcart forms no part of the claimed design.

1 Claim, 6 Drawing Sheets(56)
